UNITED STATES PATENT OFFICE

1,939,138

APPARATUS FOR TREATING LIQUID
FURNACE MATERIAL

Carl Heinrich Schol, Allendorf, Germany

Application May 20, 1930, Serial No. 454,164, and
in Germany January 28, 1930

5 Claims. (Cl. 83—91)

It is known that liquid blast furnace slag, generator slag and similar liquid furnace-materials can be swollen into a very porous mass. The usual processes and devices however are only 5 successful in the treatment of those kinds of liquid furnace-material whose chemical composition as well as high temperature are specially appropriate to the purpose. There are however a great many kinds of similar furnace-material 10 that cannot be treated by means of the usual processes and devices as they have not the appropriate composition and temperature to be easily swollen and rendered porous.

The present invention relates to an apparatus 15 which makes it possible to swell the furnace material and obtain a porous cellular structure which is hard to disintegrate and to solidify the furnace-material in this state. According to this process the mass is obtained entirely dry or nearly dry, 20 which fact increases its resistance to pressure and breaking.

The invention is illustrated diagrammatically and by way of example in the accompanying drawing.

25 Fig. 1 is a view in elevation showing one form of the apparatus.

Fig. 2 is a view in elevation showing a modified form of apparatus.

In the process according to the invention use 30 is made of a sufficiently fire-proofed wheel A (Fig. 1) which turns slowly and of which the rim is provided with a series of flat cavities a, which are filled with water or any appropriate substance b shortly before the place where they 35 receive the fall of the liquid-furnace-material. As the wheel turns, the liquid furnace-material falls down from the trough d into the cavity, where it comes into contact with the liquid required for the swelling. At this moment the 40 furnace-material swells up immediately into a spongy cellular mass and begins to solidify, while the wheel turns on and the same process takes place in the next cavity.

In order to cool down and solidify the swollen 45 mass more quickly, the hot air and gas may be removed by an exhauster e and used for other purposes. By the effect of a draught produced in this way the fresh air advances more quickly towards the wheel.

50 As the wheel goes on turning the swollen porous pumice mass falls into a pit from whence it is collected by an elevator f or any other appropriate transporting device.

It may happen that some of the solidified mass 55 remains clinging to the rim. It will then be removed by a scraper g or a little cutter like a cogged wheel which turns in the direction opposite to the rim.

While according to Figure 1 the flat bowl-shaped cavities are filled from the top by a con-

duit or pipe, this filling with liquids, vapour, gas or any other appropriate substance, can be effected under pressure from within the wheel into the incandescent furnace mass as is shown in Figure 2.

For this purpose each cavity is connected with a conduit h provided with a closing device. Each pipe may be disposed so as to be interchangeable for the frequent and easy cleaning of the same. The self-regulating closing valve may be constructed in such a manner that as a cavity reaches the operating position the corresponding little lever k slides over a guide rod i which pushes the lever k upwards and opens the valve. As soon as the furnace-material is swollen up in 75 the cavity during about a quarter of a turn of the wheel, the lever k is pushed downwards by another guide rod m so that the valve is closed again.

The present process makes it possible to fill 80 the cavities with exactly as much liquid or other substance as is required for the swelling of the liquid furnace-material. In this way it is also possible to obtain a cellular porous mass which is entirely or nearly dry, which exceedingly increases its resistance to pressure and breakage.

What I claim is:

1. An apparatus for swelling and rendering porous liquid furnace material, consisting of a wheel with flat bowl shaped cavities in its rim, 90 means for leading the liquid furnace-material into the said cavities and means for supplying said cavities in advance of the entry of said material with a limited amount of a fluid capable of swelling up said material into a cellular, porous mass, and allowing it to solidify in this state; the means for supplying the said fluid consisting of conduits leading to the bottoms of the cavities.

2. An apparatus as claimed in claim 1 in which the means for supplying the said fluid consist 100 of conduits leading to the bottoms of the cavities, of valves provided in the conduits and of means capable of operating the valves to open during about $\frac{1}{4}$ of a revolution of the wheel, and closed during about $\frac{3}{4}$ of a revolution.

3. In an apparatus as claimed in claim 1, a 105 scraping device for removing particles of slag left clinging to the wheel.

4. In an apparatus as claimed in claim 1, a device for supplying cooling air to the material 110 on the wheel.

5. In an apparatus as claimed in claim 1, a device for supplying cooling air to the material on the wheel, said device being also capable of sucking the hot air away from the material on 115 the wheel, as and for the purposes set forth.
